UNITED STATES PATENT OFFICE

152,996

DESIGN FOR A HACK SAW

Donald S. McQuillan, Springfield, Mass., assignor
to Spartan Saw Works, Inc., Springfield, Mass.,
a corporation of Massachusetts

Application July 26, 1948, Serial No. 147,770

Term of patent 14 years

(Cl. D93—3)

To all whom it may concern:

Be it known that I, Donald S. McQuillan, a citizen of the United States, residing at Springfield, in the county of Hampden and Commonwealth of Massachusetts, have invented a new, original, and ornamental Design for a Hack Saw, of which the following is a specification, reference being had to the accompanying drawing, forming a part thereof.

Referring to the drawing:

Fig. 1 is a front elevational view of a hack saw embodying my new design;

Fig. 2 is a top plan view thereof; and

Fig. 3 is an end elevational view taken from the right hand side of Fig. 1.

The essential features of the design reside in those portions shown by full lines in the drawings.

I claim:

The ornamental design for a hack saw as shown and described.

DONALD S. MCQUILLAN.
